JUG

Heinrich Riemerschmid, Munich, Germany, assignor to Anton Riemerschmid Kommanditgesellschaft, Munich, Bavaria, Germany, a limited partnership of Germany

Application February 10, 1951, Serial No. 14,175
In Germany May 2, 1950

Term of patent 14 years

(Cl. D58—6)

To all whom it may concern:

Be it known that I, Heinrich Riemerschmid, a citizen of Germany, residing at Munich, Bavaria, Germany, have invented a new, original, and ornamental Design for a Jug, of which the following is a specification, reference being had to the accompanying drawings, forming a part hereof.

Fig. 1 is a side perspective of a jug, showing my new design;

Fig. 2 is a side perspective of the jug as it appears when taken from a point diametrically opposite to that from which Figure 1 was taken.

I claim:

The ornamental design for a jug, as shown.

HEINRICH RIEMERSCHMID.
